TOY PARACHUTE AND PROJECTING MEANS
THEREFOR

Albert R. C. Giese, McKeesport, Pa.

Application October 4, 1932. Serial No. 636,224

7 Claims. (Cl. 46—52)

This invention relates to the class of toy parachutes and means for projecting the same and relates particularly to a parachute which is designed to be projected into the air in folded condition and within a casing.

The primary object of the present invention is to provide a toy parachute which may be thrown into the air in folded condition and in a casing and which will be automatically released as soon as the upward or horizontal flight of the casing changes to a downward direction.

Another object of the invention is to provide in an automatically released toy parachute, a novel means for housing the parachute and for effecting its release in the air.

A still further object of the invention is to provide a toy parachute of the character above described, in which its release to permit it to open in the air is controlled by the position 20 of its carrying case in the air.

Another object of the invention is to provide a novel projecting means for the parachute carrying case whereby its flight into the air to an extreme height is effected.

The invention will be best understood from a consideration of the following detailed description taken in connection with the accompanying drawings forming part of this specification, with the understanding, however, that the invention 30 is not confined to any strict conformity with the showing of the drawings but may be changed or modified so long as such changes or modifications mark no material departure from the salient features of the invention as expressed in 35 the appended claims.

In the drawings:—

Figure 1 is a view in side elevation of the parachute projecting mechanism showing a 40 parachute carrying casing in broken lines in position thereon;

Figure 2 is a view in top plan of the projecting mechanism;

Figure 3 is a sectional view taken substantially upon the line 3—3 of Figure 2;

Figure 4 is a view in side elevation of the 45 parachute carrier or casing;

Figure 5 is a view in top plan of the casing;

Figure 6 is a view in longitudinal section of the 50 casing on an enlarged scale showing the parachute folded therein;

Figure 7 is a sectional view taken upon the line 7—7 of Figure 6;

Figure 8 is a view in detail of one end of the 55 casing securing means.

Referring now more particularly to the draw-

ings wherein like numerals of reference indicate corresponding parts throughout the several views, the numeral 1 indicates generally the parachute case projecting mechanism which as shown is in the form of a gun or rifle having the stock portion 60 2 and the barrel portion 3.

At the forward end of the stock portion a chamber is formed therein as indicated at 4 which opens downwardly through the lower edge and which has pivotally mounted therein upon 65 the pin 5, the trigger 6. The upper end of the trigger 6 has a plate 7 which bears against the under side of one end of a bar 8 which is pivotally mounted substantially midway of its ends between the side walls of the chamber 4 as indicated at 9.

At the forward end of the chamber 4 there is formed a passage or bore 10 which opens through the top and bottom edges of the rear part of the barrel portion of the gun and into which the forward edge of the chamber 4 opens. In the upper end of this bore is a sleeve 11 and reciprocably mounted in this sleeve is a release pin 12, the upper end of which normally projects above the top edge of the barrel portion of the projector 75 while the lower end is bifurcated as indicated at 13 and receives the forward end of the oscillating bar 8 to which it is pivotally attached, as indicated at 14.

The lower edge of the projector has attached 80 thereto the trigger guard 15 the ends of which are secured in the manner shown and the forward end of this guard covers the lower end of the bore 10 and retains in position therein the expansion spring 16 which engages the lower end 85 of the release pin 12 and normally urges the same upwardly to project beyond the top of the projector.

Upon the top of the projector at the forward end of the stock and rearwardly of the pin 12 is 90 secured one end of a relatively long rearwardly projecting platform 17. The rear end of this platform is provided with the lateral ears 18 which are turned upwardly to form the guards 95 19.

At its forward end the barrel portion of the projector is provided with a transverse bore 20 into which opens the forwardly directed slot 21 and in this bore is held by a pin 22 one end of a tongue 23 which has its other ends secured in 100 a suitable manner to one end of the relatively heavy elastic band or strap 24. At its other end this elastic strap is secured to a rear tongue 25 which in turn is attached in a suitable manner, as by the use of rivets or the like, to a sling 110

plate 26. This plate 26 has an aperture 27 therein which is designed to register with the upper end of the bore 10 and to have the upper end of the pin 12 engage therein when the strap 24 has 5 been stretched to a taut condition and disposed in the position upon the top of the barrel 3 in which it is shown in Figure 1.

The plate 26 has the laterally projecting ears 28 which serve to maintain it in a horizontal 10 position or in a plane parallel with the top surface of the barrel 3 when it is released and drawn forward by the contraction of the strap 24.

Upon the top of the plate 26 at the rear thereof and upon the longitudinal center of the same 15 and the strap 24 is pivotally mounted at the point 29 the shank 30 of a hook 31.

The device which carries the toy parachute in folded condition and which is projected into the air by the structure shown in Figures 1 to 20 3 inclusive, is indicated generally by the numeral 32 and is shown in dotted lines mounted in position upon the gun in Figure 1, ready to be projected therefrom. This carrier or receptacle for the folded parachute is in the form of an arrow, 25 having the head portion 33, the narrow intermediate portion 34 and the broad relatively flat rear portion 35.

This carrier is in the form of a hollow shell and is cut transversely along the line 36 from 30 one side to substantially the longitudinal center and from this point it is divided along the line 37 to the rear end, thus forming a removable rear cover portion 38 which is pivotally joined to the corresponding underlying portion by the 35 hinge 39. There is thus formed the rear chamber 40 of which the portion 38 constitutes the cover, in which is housed a folded parachute 41 which is provided with shroud cords 42 which are attached to the bottom portion by means 40 of the eye 43.

Within the top of the forward or head portion 33 and upon the longitudinal center of the parachute carrier there is formed a pocket 44 which communicates with a channel 45 which is also formed in the head, which extends forwardly to 45 a point adjacent the tip thereof where it terminates in the opening 46 which extends through to the interior of the head.

Oscillatably mounted upon a pin 47 which is 50 secured to the head across the opening 46, is the upper end of a plate 48 which merges, exteriorly of the head, into the rearwardly extending curved arm 49 which normally lies in the channel 45 and terminates adjacent the 55 pocket 44. At the rear terminal end of this arm 49 is a disk weight 50 which lies in the pocket 44 and which has a notch cut in its edge at a point opposite the connection of the arm 49 therewith, which provides the shoulder 51. The top of this 60 shoulder 51, when the weight is in position in the pocket, is flush with the top of the head 33 and is engaged by the fan-like retaining plate 52. This plate 52 is pivotally attached or secured by the pin or rivet 53, at its radial center, 65 to the top of the head 33 upon the longitudinal center thereof and integral with this plate is a stem 54 which terminates in a flat weight 55.

Upon the longitudinal center of the carrier 70 rearwardly of the weight 55 the top wall of the head is provided with the slot or opening 56 and secured transversely of this opening 56 is a pin 57 on which is oscillatably mounted at a point intermediate its ends, the trigger arm 58 which has one end extended downwardly into the 75 interior of the head while its other end has in-

tegrally connected therewith the curved finger 59 which normally is directed downwardly into the head and has its tip positioned in the opening 56.

Within the head is a rod 60, one end of which 80 is pivotally attached as at 61 with the inner end of the plate 48, while its other end is pivotally attached as indicated at 62 to the inner end of the trigger arm 58.

Upon the under side of the body beneath the forward or free end of the cover 38 is an eye 63 to which is connected one end of an elastic band 64. The other end of this band is connected with one eye of a double eye member 65 and the other eye of this member is designed to receive the tip 90 of the trigger finger 59 as will now be explained.

In the use of the present toy parachute the 95 parachute 41 is folded in any suitable manner and placed within the chamber 40 with the shroud cords 42 connected with the eye 43 in the manner illustrated. The cover 38 is then closed and the elastic band or cord is then given one or two turns in a stretched condition about the free forward end of the cover and the underlying body portion and the free eye of the element 65 100 is then slipped over the free end of the trigger finger 59 which is then extended into the opening 56 in the manner shown in Figure 6 so that the eye will be firmly held. It will, of course, be understood that when the trigger finger 59 is 105 swung out of the opening 56 for the attachment of this eye thereto it will be necessary to oscillate the weight 55 so as to remove the fan-like plate 52 from the shoulder of the weight 50 and then swing the weight 50 out of its pocket so as to 110 oscillate the plate 48 and allow the rod 60 to shift rearwardly.

The replacement of the finger tip in the opening 56 will restore the weight 50 to its position 115 in the pocket 44 and the weight 55 is then swung back so that the stem 54 will lie parallel with the longitudinal center of the parachute carrier, in which position the plate 52 will engage over the shoulder 51 and hold the several parts against 120 movement.

The arrow is then placed in position upon the 125 platform 17 of the projector in the manner shown in Figure 1 with the hook 31 engaged in the recess 66 which is formed in the bottom wall of the head portion 33. By directing the barrel portion 3 of the projector upwardly at the desired inclination and pulling upon the trigger 6 the pin 12 will be drawn downwardly and the plate 26 released so that the band 24 will be permitted to contract and thus throw the plate and hook 130 31 forwardly. This will result in a whipping or snapping of the free end of the band and the projection into the air of the parachute containing body 32.

During its flight upwardly the parachute containing body will maintain a position in the air such that the members 52, 54 and 55 will remain in alignment longitudinally of the arrow and the trigger mechanism 59 will remain set. As the 135 arrow body turns in the air to descend a slight side swaying or tipping thereof will result in the swinging of the weight 55 and the oscillation of the fan-like plate 52 so that it will move from over the shoulder 51 of the weight and release the weight.

As the head 33 of the device turns downwardly the weight 50 will fall forwardly and this will result in the shifting of the rod 60 and the oscillation of the trigger arm 58 so as to remove the tip of the trigger finger 59 from the opening 56 140 145 150

and release the outer ring of the element 65 therefrom. The contracted band 64 will then unwrap itself from about the constricted portion 34 of the arrow so as to release the cover 38 and 5 allow the folded parachute to drop out of the chamber 40. This will result in the unwinding of the shroud cords from the folded parachute so that the latter may open and let the arrow or 10 housing for the parachute descend slowly to the ground.

The top of the head portion 33 has two pins 65 mounted therein each upon one side of the weight 50. These pins act as stops to prevent 15 the weight 55 swinging around to the point where it might interfere with the proper operation of the arm and weight 49-50.

Having thus described the invention, what is claimed is:—

1. In a toy article designed to be projected 20 into the air, an elongated hollow body, means constituting a cover for the body at one end, means for latching said cover in closed position, means for projecting the body into the air, and weight means shiftably carried by the body and 25 normally holding the latch in set position and shifting when the body assumes a predetermined position, for the release of said latching means.

2. A toy parachute of the character described, 30 comprising an elongated hollow body divided longitudinally from one end inwardly to a point substantially midway of its ends, one of the portions formed by such division being pivotally connected at one end to the body and constituting a closure member, a parachute folded within the 35 body and connected therewith and adapted to be released therefrom upon the opening of said closure member, pivoted means normally retaining said closure member in closed position, and means normally holding the pivoted means in 40 closed position and releasing the same upon the assumption by the body of a predetermined position in the air, to permit said closure means to open.

3. In a toy parachute of the character described, 45 an elongated hollow arrow-like body having a portion of its rear end removable, said removable portion constituting a closure for the body, a parachute folded within the body and connected therewith and adapted to leave the 50 same upon the opening of the closure member, a latch finger oscillatably mounted upon the body, means for retaining said closure member in closed position, said means being normally held by the latch finger, an arm member oscillatably mounted upon the head end of the body, connecting means between the arm and the latch for effecting the oscillation of the latter and release of the closure member retaining means, and a gravity 55 actuated element carried upon the head end of the body and normally holding the arm against movement.

4. In a toy parachute device of the character 60 described, an elongated hollow body having a

head end and having a removable rear end portion pivotally joined thereto, a parachute housed within the rear end of the body for escape therefrom upon the removal of said portion, a retaining band adapted to be wrapped about the body 80 to overlie and hold said removable portion in position thereon, an oscillatable latch element normally engaging and holding said band in operative position, a weighted arm member pivotally mounted upon the head end of the body to 85 swing outwardly therefrom, means connecting said arm for positively actuating said latch element, and a weighted member oscillatably mounted upon the head end of the body and normally retaining said weighted arm against 90 movement.

5. A toy projectile, comprising an elongated casing having a movable cover portion at one end, a parachute adapted to be folded and housed in the casing for escape therefrom when the cover portion is open, a member oscillatably mounted upon the casing and having a portion outside the same, means associated with said outside portion of said member for retaining said cover closed, a lever oscillatably mounted on the casing, 100 a link connection between said lever and the inner end of the member, weight means operating to swing said lever for the oscillation of said member when the casing assumes a predetermined position in the air, and gravity actuated means carried by the casing and holding said lever against movement until the casing assumes the said predetermined position.

6. A toy projectile, comprising an elongated casing having a pointed end and having a cover 110 adjacent the opposite end, a parachute adapted to be folded in the casing for discharge therefrom when the cover is open, a member oscillatably mounted on a wall of the casing and having a portion exteriorly thereof, means engaged 115 by the exterior portion of said member for retaining said cover closed when the member is in one position, a weighted lever pivotally mounted upon the pointed end of the casing, a link connection between the lever and said member 120 whereby the swinging of the lever under the influence of the weight will shift said member to release the cover, and a gravity actuated weight pivotally mounted upon the casing and adapted to engage said lever to hold the same against 125 movement and to shift for the release of the lever when the casing assumes a predetermined position.

7. In a device designed to be projected into the air, an elongated hollow body, means for opening the body, a parachute folded within the body and connected therewith, latching means normally preventing the opening of the body, and gravity operated means carried by said body and normally connected with the latching means and 135 adapted to release the same when the body assumes a predetermined position in the air.
